UNITED STATES PATENT OFFICE.

JOHN ELLIS GAFFNEY, OF BIRMINGHAM, ENGLAND, ASSIGNOR TO J. H. TUCKER & COMPANY LIMITED, OF BIRMINGHAM, ENGLAND.

TERMINAL FOR ELECTRICAL ACCESSORIES.

Application filed December 18, 1924, Serial No. 756,173, and in Great Britain March 26, 1924.

My invention is for improvements in terminals for electrical accessories, and has for its object the provision of a terminal which will render the connection of a lead to a 5 terminal instrument more easily effected than is the case with terminals at present in use. For example, in electrical switches which are mounted in terminal boxes, it is at present often necessary to remove the 10 switch from the box in order to connect the end of a lead to the switch, whereafter the switch has to be replaced in the box. This operation involves a considerable amount of time and labour and the present invention 15 aims at reducing the amount of time and labour necessary in effecting these operations.

The present invention consists of an electric terminal for use with an electrical accessory, wherein that portion of the accessory which is adapted to grip the electric lead may be attached to or detached from the portion which is normally in rigid connection with the circuit of the accessory 25 without disturbing the elements in the circuit of the accessory from their normal position.

Again, the present invention consists in an electric switch so constructed that the 30 portion which grips the electric leads may be attached to or detached from the switch without disturbing the switch contacts from their normal working position.

Further, the present invention consists of 35 a plug-and-socket terminal for an electrical accessory, wherein the socket is adapted to be rigidly secured in position upon an electrical accessory, so as to be in electrical connection with the circuit thereof, and the 40 plug is adapted to be removed from the socket to permit a lead to be readily connected thereto so as to be in electrical connection with the accessory when the plug is inserted in the said socket.

Again, the present invention comprises an 45 electrical accessory wherein a plug-and-socket terminal, such as set forth in the preceding paragraph, is employed.

The invention is more particularly de- 50 scribed with reference to the accompanying drawings, in which:—

Figure 1 illustrates in plan view a tumbler switch mounted in a terminal box, wherein the terminals connected with the stationary 55 contacts of the switch comprises a plug-and-

socket terminal constructed according to the present invention, and

Figure 2 is a sectional elevation on the line A—A of Figure 1.

In the drawings, which illustrate one embodiment of the invention, a tumbler switch 1 is mounted in a terminal box 2, into which a pair of leads 3 are led. The tumbler switch 1 may be of any desired construction, and the incoming leads 3 are adapted to be secured in plugs 4 adapted to frictionally engage with a pair of sockets 5, each adapted to be secured in electrical connection with one of the fixed contact springs 6 of the switch 1. The socket 5 comprises a 70 hollow tube provided with a flange 7 at one end thereof, and screw-threaded on its external surface at the end remote from the flange 7. The socket 5 is adapted to receive the fixed contact springs 6 of the switch 75 and to be inserted into a hole 9 in the insulating base 8 of the switch, and thereafter clamped to the base with the contact springs 6 firmly held underneath the flange 7 by a nut 10 engaging with the screw-threaded end of the socket 5. Adapted to be inserted into the socket 5 is the plug 4, one end of which comprises a bifurcated member 11, the limbs of which are adapted to be pressed into the socket 5 and held 85 firmly therein by the resiliency of the bifurcated limbs 11. At the end remote from the bifurcated limbs 11 there is provided a transverse hole 12 adapted to receive one of the leads 3 and a binding screw 13 is 90 arranged to extend into the said hole in the direction of the longitudinal axis of the said plug, which screw is adapted to be tightened up so as to clamp the lead 3 in the transverse hole 12 hereinbefore referred to. 95

The head of a screw is mounted in an insulating cup 14, the sides of which extend upwardly beyond the head of the screw so as to prevent the cover 15 of the terminal box coming in contact with the head of the 100 screw 13. The cover 15 is adapted to bear against the free end of the insulating cup 14 so that when the terminal box 2 is closed, the plug 4 is firmly held in the socket 5 and prevented from accidentally being removed 105 therefrom.

Thus it will be seen that when a switch is provided with a plug and socket terminal of the character hereinbefore mentioned, it is not necessary to remove the switch from 110

the terminal box when connecting a lead thereto, as it is only necessary to remove the plug of the terminal from the socket thereof, and connect the lead to the said plug, where-
5 after the same may be pressed into the socket and provide the necessary connection in a simple and efficient manner, thereby eliminating a considerable amount of time and labour.

10 What I claim as my invention and desire to secure by Letters Patent is:—

1. In combination, a terminal box, switch mechanism mounted therein, a socket terminal fixedly positioning contacts for the
15 switch mechanism, a plug terminal having an electrical lead detachably secured therein and adapted to make electrical connection with said socket terminal, and means comprising the terminal box cover for maintaining said plug and socket terminals in position.

2. In a switch mechanism, a terminal box, switch mechanism mounted therein, a socket terminal fixedly positioning contacts for the
25 switch mechanism, a plug terminal having an electrical lead detachably secured therein and adapted to contact with said socket ter-

20 minal, an insulating device secured to the upper end of said plug terminal, and adapted to be contacted with by the terminal box 30 cover in order to maintain said terminals securely in position.

3. In a plug and socket electrical connection, the combination with a box and a cover therefor, of a plug having a slot therein for imparting springiness to the plug, an opening within the upper end of the plug for receiving an electrical lead, another opening within the upper end screw-threaded to receive a securing means for detachably securing the electrical lead in place, an insulating device for insulating the upper end of the plug said device having an opening therein adapted to be juxtaposed with the screw-threaded opening for permitting said insulating device to be secured in position between the electrical lead securing means and the plug and adapted to be contacted with by said box cover in order to maintain the plug securely in position.

50 In witness whereof I have hereunto set my hand.

JOHN ELLIS GAFFNEY.
